UNITED STATES PATENT OFFICE

149,860

DESIGN FOR A CONFECTIONERY DISPLAY STAND

Fred L. Daggett, Newton, Mass., assignor to Daggett Chocolate Company, Cambridge, Mass., a corporation of Massachusetts

Application March 26, 1946, Serial No. 127,951

Term of patent 14 years

(Cl. D80—11)

To all whom it may concern:

Be it known that I, Fred L. Daggett, a citizen of the United States, residing at Newton, in the county of Middlesex and State of Massachusetts, have invented a new, original, and ornamental Design for Confectionery Display Stand, of which the following is a specification, reference being had to the accompanying drawing, forming part thereof.

In the drawing, the figure is a front perspective view of a confectionery display stand showing my new design.

I claim:

The ornamental design for a confectionery display stand, substantially as shown.

FRED L. DAGGETT.
